METHOD AND APPARATUS FOR MAKING
RUBBER MASKS AND SIMILAR ARTICLES

Merrill E. Hansen, Akron, Ohio, assignor to American Anode Inc., Akron, Ohio, a corporation of Delaware

Original application April 6, 1940, Serial No. 328,331. Divided and this application July 5, 1940, Serial No. 343,920

16 Claims. (Cl. 18—41)

This invention relates to masks covering the nose and mouth of the wearer and particularly to masks of the type worn by aviators for high altitude flying, and to an apparatus and method for making the same.

In this invention I have perfected a nose and mouth mask of a type that is worn, for example, by aviators when flying at high altitudes to supply additional oxygen. In the mask I have also incorporated voice-transmitting means so that the wearer may be able to speak intelligibly, as into a radio transmitter, without necessitating the removal of the mask. Similarly, I have invented an apparatus and perfected a method for making these nose and mouth masks in a simple, economical and efficient manner.

Generally, the nose and mouth mask that is the subject of this invention comprises a nose covering portion, a mouth covering portion, a voice transmitting means associated with the mouth covering portion, and a breathing tube associated with the mouth covering portion. To make these masks I provide a principal deposition form comprising a bulbous portion and a ring-like structure, and a complementary form adapted to matingly fit the ring-like structure of the principal form. I cover the two forms separately with individual coatings of rubber as by dipping them in a coagulant solution for latex (such as any of those disclosed in U. S. Patent No. 1,996,090, granted April 2, 1935, to Edward A. Willson) and then dipping in latex. The forms are then fitted together in their mating relationship and coated with an overall layer of rubber by the same method. The forms are removed from the rubber deposits and the article is trimmed to produce the completed mask.

The various procedural steps used in the manufacturing operations, as well as the apparatus used and the resulting product of this invention can best be understood by reference to the accompanying drawings, of which

Fig. 1 is an elevation of the principal deposition form mounted on a support and immersed in a body of latex;

Fig. 2 is an elevation of the complementary deposition form mounted on a support and immersed in a body of latex;

Fig. 3 is a cross-sectional elevation of the rubber coated forms assembled in mating relationship and immersed in a body of latex;

Fig. 4 is an elevation of the apparatus of this invention coated over-all with rubber and with a portion of the rubber broken away for clarity of illustration;

Fig. 5 is an elevation showing an operation preparatory to removing the forms from the rubber coatings;

Fig. 6 is a cross-sectional elevation of the complementary form of the apparatus of this invention taken along line 6—6 of Fig. 2 and showing particularly the portion of the form used in making the housing for the voice transmitting means;

Fig. 7 is an elevation illustrating the removal of a portion of the principal form from the rubber coating;

Fig. 8 is an elevation in profile of the nose and mouth mask of this invention;

Fig. 9 is a rear elevation of the nose and mouth mask of this invention;

Fig. 10 is a cross-sectional elevation of the nose and mouth mask of this invention taken along line 10—10 of Fig. 9 with a preferred voice-transmitting means in place;

Fig. 11 is a cross-sectional elevation of the two projecting portions of the nose and mouth masks showing specifically a modified form of voice-transmitting means.

In manufacturing the nose and mouth masks of this invention, I use an apparatus on which rubber is deposited from latex and this apparatus comprises two forms, one a principal form 20 and the other a complementary form 21. The principal form 20 comprises a bulbous portion 22, with two rod-like arms projecting from spaced apart points on the bulbous portion and merging to form a ring-like structure 23 lying in a concave plane. Also, a fin-like portion 24 is provided on the bulbous portion 22 opposite to and projecting away from the ring-like structure 23. The principal form 20 constitutes two elements (Fig. 4) joined, as with dowel pins, at two points 30, 31 lying in a planar relationship on the ring-like structure 23 to form a unitary structure with one point 31 adjacent the bulbous portion 22 and the other point 30 opposite the bulbous portion. The complementary form 21 is adapted to matingly fit the ring-like structure 23 of the principal form 20 and comprises an element 25 with a concave surface 26 and a convex surface 27. The convex surface has two projecting portions 34 and 51. The projecting portion 34 is cylindrically shaped and located near the hollowed out portion of the periphery. The other projecting portion 51 is generally cylindrical and is provided with at least one circumferentially raised section 52. The complementary form 21 has a generally elliptical outline with a substantial portion of the periphery 28 hollowed out to fit the ring-like structure 23. The remainder of the

periphery 28 is generally flattened as indicated at 29 to fit the bulbous portion 22 of the principal form 20 between the rod-like arms that constitute the ring structure 23.

In a preferred method of practicing this invention the principal form 20 is mounted on a support 32 with the ring structure 23 directed upward so as to lessen the danger of the ring structure accidentally becoming separated at the points of joinder 30, 31. The complementary form 21 is mounted on a support 33 through the rod-like projecting portion 34. The two forms are coated with rubber as by dipping in a latex coagulant and in latex. The two forms are then arranged in mating relationship and dipped again (Fig. 3). The complementary form 21 fits in the ring-like structure 23 forming a compact assembly. The rubber is then washed and dried on the forms, after which the rubber deposit is cut around the flat back of the bulbous portion 22 and fin portion 24 and also around the ring structure 23 on the convex side 36. The ring structure is broken loose into its two elements 37, 38 by pulling the elements apart. The bulbous portion with its attached arm of the ring portion 37 is removed and then the complementary form 21 is removed by pushing it out through the back and through the ring-like rubber deposit 39, after which the rest of the ring structure 38 is removed from the rubber article.

After the forms 20, 21 are removed the rubber is trimmed round the bulbous portion, the section of rubber 40 between the bulbous portion and the complementary form is cut out, the ends of the projecting portions are trimmed off, and the rubber article is vulcanized. The edge around the bulbous portion 43 is then smoothed to a feather edge 44 as by buffing with a buffering wheel 42. (Fig. 10).

The resulting nose and mouth mask proper as shown in Figs. 8 and 9 is a unitary integral structure made up of one continuous piece of rubber. The mask comprises a bulbous portion 43 adapted to fit over the nose, a tubular cushion 44 that fits the face around the mouth, and a portion 45 to cover the mouth. On this mouth covering portion 45 are two projecting portions, one of which is tubular 46 located adjacent the tubular cushion and serves as a means for admitting oxygen to the wearer of the mask. This breathing tube may be located at any point on the mask, such as projecting from the tubular cushion, in which case the oxygen would be led through the breathing tube and the tubular cushion into the interior of the mask. The other projecting portion 47 is generally tubular but with at least one section 48 internally recessed circumferentially to hold the voice transmitting means. This voice transmitting means is preferably a disc of sponge rubber 49 (Fig. 10) which may or may not be cemented or otherwise adhered to the walls of the tubular portion. As an alternate means for voice transmission, the tubular projection may be closed with an integral rubber diaphragm 50 formed as a continuation of the rubber walls of the tubular portion as shown in Fig. 11. Preferably, although not necessarily, the rubber diaphragm as well as the preferred sponge rubber disc voice transmitting means are located a substantial distance back from the outer end of the tubular projection as shown in Figs. 10 and 11 in order that the voice transmitting means shall be effectively protected from contacting other objects, such as a microphone held by the aviator, which would

interfere with satisfactory sound transmission. This spacing feature is especially important in the diaphragm embodiment of Fig. 11.

It is understood that although the apparatus, method of making, and resulting nose and mouth mask have been described in considerable detail with reference to the accompanying drawings, many variations may be effected in all such details without departing from the spirit and scope 10 of the invention as defined by the appended claims.

This application is a division of my copending application Serial No. 328,331, filed April 6, 1940.

I claim:

15. 1. A method of making rubber articles comprising providing a principal deposition form comprising a ring-like structure, coating the principal form with rubber, providing a complementary form adapted to matingly fit the ring-like structure of the principal form, coating the complementary form with rubber, associating the coated principal and complementary forms in mating relationship with the complementary form closing the opening in the ring-like structure of the principal form, and coating the assembled structure with rubber.

2. A method of making nose and mouth masks comprising providing a principal deposition form comprising a bulbous portion with two rod-like

30 arms projecting from spaced apart points on the bulbous portion merging to form a ring-like structure, providing a complementary deposition form adapted to matingly fit the ring-like structure of the principal form and comprising an

35 element with a concave surface and a convex surface having a generally elliptical outline with a substantial portion of the periphery hollowed out to fit the ring-like structure of the principal deposition form, dipping the principal form

40 in an aqueous dispersion of rubber, dipping the complementary form in an aqueous dispersion of rubber, associating the complementary form with the principal form in mating relationship with the hollowed out periphery of the complementary

45 form embracing the arms of the ring-like structure and the complementary form closing the opening in the ring-like structure of the principal form, and dipping the assembled structure in an aqueous dispersion of rubber to give a

50 unitary overall deposit of rubber, and drying and vulcanizing the deposited layers of rubber.

3. A method of making nose and mouth masks comprising providing a principal deposition form comprising a bulbous portion with two rod-like

55 arms projecting from spaced apart points on the bulbous portion and merging to form a ring-like structure lying in a concave plane, providing a complementary form adapted to matingly fit the principal form and comprising an element with

60 a concave surface and a convex surface, said complementary form having a generally elliptical outline with a substantial portion of the periphery hollowed out to fit the ring-like structure of the principal form and with the remainder

65 of the periphery generally flattened to fit the area of the bulbous portion of the principal form between the rod-like arms, coating the principal form with latex rubber, coating the complementary

70 form with latex rubber, associating the complementary form with the principal form in mating relationship with the hollowed out portion of the complementary form embracing the arms of the principal form, and coating the assembled apparatus with latex rubber to give a

unitary overall deposit of rubber, and drying and vulcanizing the rubber deposits.

4. A method of making nose and mouth masks which comprises providing a principal deposition form comprising a bulbous portion with two rod-like arms projecting from spaced apart points on the bulbous portion and merging to form a ring structure lying in a concave plane, a fin-like portion on the bulbous portion opposite to and projecting generally away from the ring-like structure, said principal form comprising two elements separably joined at two points lying in a planar relationship on the ring-like structure to form a unitary structure with one point adjacent the bulbous portion and the other point opposite the bulbous portion, providing a complementary deposition form adapted to matingly fit the ring-like structure of the principal form and comprising a member with a concave surface and a convex surface, said complementary form having a generally elliptical outline with a substantial portion of the periphery hollowed out to fit the ring-like structure of the principal form and with the remainder of the periphery generally flattened to fit the area of the bulbous portion between the rod-like arms, a cylindrically-shaped projecting portion on the convex surface adjacent the hollowed out portion of the periphery, and a second cylindrically-shaped projecting portion adjacent the flat portion of the periphery, said second projecting portion comprising at least one circumferentially raised section, immersing the principal deposition form in latex, immersing the complementary deposition form in latex, associating the complementary form in mating relationship with the principal form, immersing the associated forms in latex to produce an overall coating of rubber, drying the rubber deposits and removing the forms from the rubber deposit by cutting around the back section of the bulbous portion, separating the principal deposition form into its two elements at the points of joinure on the ring-like portion, removing the bulbous portion and the attached rod-like arm through the cut section, cutting a second opening around the deposited rubber at the ring-like structure on the convex side of the ring-like structure, removing the complementary form through this opening, and removing the remainder of the ring-like structure through the cut section on the back of the bulbous portion.

5. Apparatus for making nose and mouth masks comprising a principal deposition form comprising a ring-like structure and a complementary deposition form adapted to matingly fit the ring-like structure of the principal form, said complementary form including a continuous surface substantially co-extensive with the opening in the ring-like structure of the principal form whereby, in the assembled apparatus, the complementary form substantially closes the opening in the ring-like structure of the principal form.

6. Apparatus for making nose and mouth masks comprising a principal deposition form comprising a bulbous portion with two rod-like arms projecting from spaced apart points on the bulbous portion and merging to form a ring-like structure, and a complementary deposition form adapted to matingly fit the ring-like structure of the principal deposition form and comprising an element with a concave surface and a convex surface having a generally elliptical outline with a substantial portion of the periphery

hollowed out to fit the ring-like structure of the principal deposition form.

7. Apparatus for making nose and mouth masks comprising a principal deposition form comprising a bulbous portion with two rod-like arms projecting from spaced apart points on the bulbous portion and merging to form a ring-like structure lying in a concave plane, and a complementary form adapted to matingly fit the principal form and comprising an element with a concave surface and a convex surface, said complementary form having a generally elliptical outline with a substantial portion of the periphery hollowed out to fit the ring-like structure of the principal form and with the remainder of the periphery generally flattened to fit the area of the bulbous portion of the principal form between the rod-like arms.

8. Apparatus for making nose and mouth masks comprising a principal deposition form comprising a bulbous portion with two rod-like arms projecting from spaced apart points on the bulbous portion and merging to form a ring-like structure lying in a concave plane, a fin-like portion on the bulbous portion opposite to and projecting generally away from the ring-like structure, and a complementary form adapted to matingly fit the ring-like structure of the principal form and comprising an element with a concave surface and a convex surface, said complementary form having a generally elliptical outline with a substantial portion of the periphery hollowed out to fit the ring-like structure of the principal form and with the remainder of the periphery generally flattened to fit the bulbous portion in the area between the rod-like arms; the apparatus being capable of being assembled with the concave surface of the complementary form next the ring-like structure of the principal form and the convex surface of the complementary form away from the ring-like structure of the principal form.

9. Apparatus for making nose and mouth masks comprising a principal deposition form comprising a bulbous portion with two rod-like arms projecting from spaced apart points on the bulbous portion and merging to form a ring-like structure lying in a concave plane, a fin-like portion on the bulbous portion opposite to and projecting generally away from the ring-like structure, said principal form comprising two elements separably joined at two points lying in a planar relationship on the ring-like structure to form a unitary structure with one point adjacent the bulbous portion and the other point opposite the bulbous portion, and a complementary form adapted to matingly fit the ring-like structure of the principal form and comprising a member with a concave surface and a convex surface, said complementary form having a generally elliptical outline with a substantial portion of the periphery hollowed out to fit the ring-like structure of the principal form and with the remainder of the periphery generally flattened to fit the area of the bulbous portion between the rod-like arms, a cylindrically-shaped projecting portion on the convex surface adjacent the hollowed out portion of the periphery, and a second projecting portion adjacent the flat portion of the periphery, said second projecting portion comprising at least one circumferentially raised section; the apparatus being capable of being assembled with the concave surface of the complementary form next the ring-like structure of the principal form and the convex surface with the projecting portions away

from the ring-like structure of the principal form.

10. A method of making nose and mouth masks comprising providing a principal deposition form comprising a bulbous portion with two rod-like arms projecting from spaced apart points on the bulbous portion and merging to form a ring-like structure lying in a concave plane, a fin-like portion on the bulbous portion opposite to and projecting generally away from the ring-like structure, providing a complementary deposition form adapted to matingly fit the ring-like structure of the principal form, coating the principal form with latex rubber, coating the complementary form with latex rubber, associating the coated complementary form with the coated principal form in mating relationship with the complementary form closing the opening in the ring-like structure of the principal form, and coating the assembled structure with latex rubber.

11. A method of making nose and mouth masks comprising providing a principal deposition form comprising a bulbous portion with two rod-like arms projecting from spaced apart points on the bulbous portion and merging to form a ring-like structure lying in a concave plane, said principal form comprising two elements separately joined at two points lying in a planar relationship on the ring-like structure to form a unitary structure, providing a complementary deposition form adapted to matingly fit the ring-like structure of the principal form and comprising an element with a concave surface and a convex surface, said complementary form having a generally elliptical outline with a substantial portion of the periphery hollowed out to fit the ring-like structure of the principal form and with the remainder of the periphery generally flattened out to fit the area of the bulbous portion of the principal form between the rod-like arms, immersing the principal deposition form in latex, immersing the complementary deposition form in latex, associating the complementary form in mating relationship with the principal form, immersing the associated forms in latex to produce an overall coating of rubber, drying the rubber deposits and removing the forms from the rubber deposit by cutting around the back section of the bulbous portion, separating the principal deposition form into its two elements at the points of joinure on the ring-like portion, removing the bulbous portion and the sections of attached rod-like arms through the cut section, cutting a second opening around the deposited rubber at the ring-like structure on the convex side of the ring-like structure, removing the complementary form through this opening, and removing the remainder of the ring-like structure through the cut section on the back of the bulbous portion.

12. A method of making a mask or similar article which comprises producing a rubber element including a hollow bulbous portion and a curved tubular portion communicating with the bulbous portion to provide a ring-like hollow rubber element, producing a second hollow rubber element having an exterior configuration adapted to mate with the aforesaid ring-like element,

associating the two elements in mating relationship with the second element substantially closing the opening in the ring-like element, coating the assembled elements with rubber to form a

5 unitary structure, removing a portion of the wall constituting one face of the bulbous portion of the first said element, and removing a portion of the wall constituting one face of the said second element in the region within the ring-like

10 element.

13. A method of making a mask or similar article which comprises producing a rubber element including a hollow bulbous portion and a curved tubular portion communicating with the

15 bulbous portion to provide a ring-like hollow rubber element, producing a second hollow rubber element having an exterior configuration adapted to mate with the aforesaid ring-like element, associating the two elements in mating relationship with the second element substantially closing the opening in the ring-like element, coating the assembled elements with rubber to form a unitary structure and removing a substantial portion of the wall of said

25 structure to provide an opening therein for receiving facial portions of a person wearing the mask.

14. A method of making a mask or similar article which comprises producing a hollow rubber element having a ring-like configuration, producing a second hollow rubber element having an exterior configuration adapted to mate with the aforesaid ring-like element, associating the two elements in mating relationship, coating the assembled elements with rubber to provide a unitary structure, and removing a substantial portion of the wall of said structure to provide an opening for receiving facial portions of a person wearing the mask.

40 15. A method of making a mask or similar article which comprises producing a hollow rubber element having a ring-like configuration, producing a second hollow rubber element having an exterior configuration adapted to mate with the aforesaid ring-like element, associating the two elements in mating relationship and bonding them together to provide a unitary structure, and removing a substantial portion of the wall of said structure to provide an opening for receiving facial portions of a person wearing the mask.

16. A method of making a mask or similar article which comprises producing a hollow rubber element having a ring-like configuration, producing a second hollow rubber element having an exterior configuration adapted to mate with the aforesaid ring-like element, associating the two elements in mating relationship and bonding them together to provide a unitary structure, and removing a substantial portion of the wall of said structure including adjacent portions of both the constituent elements to provide an opening for receiving facial portions of a person wearing the mask.
